(57) **CLAIM**

The ornamental design for a fishing rod with motorized reel, as shown and described.

DESCRIPTION

FIG. 1 is a right side elevation view of a fishing rod with motorized reel showing my new design;

FIG. 2 is a left side elevation view;

FIG. 3 is a front elevation view;

FIG. 4 is a rear elevation view;

FIG. 5 is a top plan view; and,

FIG. 6 is a bottom plan view of a fishing rod with motorized reel showing my new design.

The fishing rod is shown broken away for convenience of illustration.
